ATTORNEY

UNITED STATES PATENT OFFICE.

PIERRE MINAUX, OF FERRIERES, FRANCE.

APPARATUS FOR LIGHTING AND EXTINGUISHING GAS BURNERS FROM A DISTANCE.

Application filed May 9, 1923. Serial No. 637,750.

To all whom it may concern:

Be it known that I, PIERRE MINAUX, a citizen of the French Republic, and residing in Ferrieres, Loiret, France, have invented certain new and useful Improvements in and Relating to Apparatus for Lighting and Extinguishing Gas Burners from a Distance, of which the following is a complete specification.

10 This invention relates to an apparatus for lighting and extinguishing gas burners at a distance.

The invention is more particularly characterized by the fact that there is mounted 15 on the pipe which controls the supply of gas to the burner a lever and a counter-weight system which is variable and acts in opposition to the pressure of the gas for the purpose, on the one hand, of producing 20 by an increase in the pressure of the gas, the placing of the pipe in the gas distributing position, and consequently the operation of the corresponding burner, and on the other hand to ensure these parts being

25 securely held in this distributing position after the return to normal pressure in consequence of a variation, effected automatically, in the position of the lever and the counterweights.

30 In the accompanying drawing which represents a constructional example of the subject matter of the invention:

Fig. 1 is an elevation, partially in vertical section, showing the construction of the apparatus according to this invention.

Fig. 2 is a similar view of the lower part of the gas burner showing the parts in the position they occupy when the burner is in operation.

40 On the socket 1 which is intended to be fixed by screwing for example to the supply pipe (not shown) for the illuminating gas is fixed a casing 2 carrying at its upper part the burner 3 which is of the usual construction and with which it is adapted to communicate through an orifice 4, formed in the centre of its upper wall and of circular form for example. This casing 2 contains 45 at its lower part a liquid of any suitable nature, such for example as mercury, glycerine or the like into which dips a bell 5, rigidly connected to a tube 6, which in the "out" position, shown in Fig. 1, is caused by the weight of the bell 5 to immerse its 50 lower end in a capsule 7 containing a liquid

8 such as mercury, which completely cuts off the inside of the bell from the outside.

The capsule 7 is preferably mounted on the upper end of a gas supply pipe 9 provided close to its upper end with escape 60 holes 10 which open into the bell 5 and keep this latter in constant communication with the gas mains. There therefore exists constantly in the interior of this bell 5 a pressure which is determined by the 65 gas works supplying the gas.

To the pipe 6 is pivoted by one forked end a lever 11 also pivoted at 12 to a suitable bracket on the casing 2 and carrying on one screw-threaded end 13, a movable 70 counterweight 14. This lever 11 has an arm 15 provided at its end with a fixed counterweight 16, the direction of this arm 15 being such that it is practically vertical for the "out" position of the burner the 75 action of the counterweight 16 being then almost negligible. The whole is completed by a pilot light 17 of suitable construction.

The burner works as follows:

During the day, the pressure being main- 80 tained at a sufficiently low fixed value (60 mm. for example) the parts will occupy the position shown in Fig. 1. The weight of the bell 5 and of the parts which are connected to it is preponderant and keeps the 85 lower end of the pipe 6 immersed in the mercury 8 of the capsule 7. The gas escaping through the holes 10 into the interior of the bell 5 cannot consequently pass to the burners. 90

When it is desired to light the gas burners the distributing pressure is increased at the gas works so as to bring it for example from 60 mm. to 70 mm. The bell 5 is then raised and brings the pipe 6 into 95 the position shown in Fig. 2 in which the lower end of this pipe is disengaged from the mercury while its upper extremity projects through the opening 4, its movement upwards being then limited by a suitable 100 collar or flange 18. Immediately the gas passes into the burner this latter will light up in consequence of the ignition of the gas produced by the pilot light 17. During this movement of the bell 5, the lever 11 105 oscillates on its pivot 12, bringing the rod 15 into the position of Fig. 2, in which the counterweight 16, moved out of its position of equilibrium, comes into operation to keep the pipe 6 in its raised position correspond- 110

ing to the operation of the burner. This movement having been obtained, the distributing pressure is restored to its normal value (60 mm. for example). The regulation has been effected in such a way that the parts remain in the position of Fig. 2 as long as this normal pressure is maintained.

When it is desired to extinguish the burners, the distributing pressure at the gas works is brought to a suitably low value (50 mm. for example) and the weight of the bell 5 and of the parts connected thereto then become preponderant and suffice to produce a lowering of the bell and the tube 6, into the position shown in Fig. 1, raising likewise the counterweights 14 and 16.

To adjust the apparatus the pressure at the gas works is adjusted to that necessary for lighting, the apparatus being placed in the position of Fig. 1 and the counterweight 14 screwed up until it approaches near to the pivot 12. It is then screwed back slowly outwards until the bell 5 rises thus determining the working of the apparatus and the lighting of the burner 3. The counterweight 14 is then secured in any convenient manner its operation being then assured for the variation of pressure determined.

This arrangement permits of ensuring the working of the apparatus that is to say the lighting and extinguishing of the gas burners serving for example for the lighting of a town in an absolutely automatic manner by producing simply the working of these apparatus by a variation of pressure in the distributing mains from the gas works. It is also possible to divide the gas burners of a lighting system into several groups the lighting and extinguishing of which can be obtained by suitably differing pressures which will permit for example of extinguishing at any hour of the night a suitably fixed number of gas burners. The general arrangement permits also of ensuring the operation of gas burners at any desired hour of the day or night in case of need by a simple variation of the pressure carried out at the gas works.

One practical embodiment of the invention has been illustrated in the accompanying drawings by way of example but it will be understood that many modifications and adaptations thereof may be provided without departing from the spirit and scope of the invention and that I therefore consider as my own all such modifications and adaptations thereof as fairly fall within the scope of the appended claims.

What I claim is:

1. An apparatus for lighting and extinguishing gas burners comprising an axially movable bell, a feeder tube carried by the bell, said feeder tube terminating at its

inner end within the bell and at its outer end exteriorly of the bell and being adapted to conduct gas from the space within the bell to a gas burner, a gas supply tube extending into the bell, through the mouth of the latter, means surrounding the bell for holding a fluid in position to seal the mouth of the bell, means carried by the supply tube for sealing the inner end of the feeder tube when the bell is in a certain position in respect to the supply tube and for permitting passage of gas from the bell into the feeder tube when the bell has moved from said position, and gravity means adapted to act in conjunction with the pressure from said supply tube to move the bell from said certain position when a definite pressure has been reached in the bell.

2. An apparatus of the character described comprising a vertically disposed gas supply tube having a lateral port adjacent to its upper end, a bell receiving the upper end of the supply tube and being movable vertically in respect to the supply tube, a feeder tube extending through the crown of the bell in vertical alinement with said supply tube, said feeder tube being movable with the bell and being adapted to conduct gas to a gas burner, means for holding a sealing fluid in position to seal the space between the mouth of said bell and the outer wall of said supply tube, means carried at the upper end of said supply tube for holding a sealing fluid in position to seal the lower end of said feeder tube when the bell is in its lowermost position in respect to the feeder tube, said bell normally being held in its lowermost position by gravity, and gravity means connected with said feeder tube for assisting the pressure from said supply tube within said bell to raise said feeder tube above said second named sealing means when a definite pressure has been reached within the bell and to hold said feeder tube in raised position until the pressure falls below a pressure lower than said definite pressure.

3. An apparatus of the character described comprising a vertically disposed gas supply tube having a lateral port adjacent to its upper end, a bell receiving the upper end of the supply tube and being movable vertically in respect to the supply tube, a feeder tube extending through the crown of the bell in vertical alinement with said supply tube, said feeder tube being movable with the bell and being adapted to conduct gas to a gas burner, means for holding a sealing fluid in position to seal the space between the mouth of said bell and the outer wall of said supply tube, means carried at the upper end of said supply tube for holding a sealing fluid in position to seal the lower end of said feeder tube when the bell is in its lowermost position in respect to the feeder tube, said bell normally being held in

its lowermost position by gravity, a lever fulcrumed intermediate of its length at a point lateral of said feeder tube and being pivotally connected at one end to said feeder tube, a counterweight adjustably engaged with the other end portion of said lever, and a second counterweight carried by said lever nearly directly above said fulcrum when the

feeder tube is in its lowermost position and at the same side of said fulcrum as the first named counterweight when the feeder tube has been raised from its lowermost position.

In testimony I have hereunto set my hand at Paris, France, this 25th day of April, 1923.

PIERRE MINAUX.
